UNITED STATES PATENT OFFICE.

JOSEPH DELAITTRE, OF LAVAL, FRANCE.

APPARATUS FOR DRAWING OFF BEER FROM BARRELS.

SPECIFICATION forming part of Letters Patent No. 781,813, dated February 7, 1905.

Application filed August 30, 1902. Serial No. 121,677.

To all whom it may concern:

Be it known that I, JOSEPH DELAITTRE, a citizen of the French Republic, residing at La Coconniere, Laval, France, have invented certain new and useful Improvements in Apparatus for Drawing Off Beer from Barrels, of which the following is a full clear, and exact description.

The object of this draw-off is to entirely prevent frothing, the beer passing from the barrel into the bottles without any depression. For this purpose the counter-pressure in the cylinder and bottles is no longer produced by the beer, but by a liquid termed the "compensating" liquid, (glycerinated water.) As the beer does not froth, two cocks instead of four or six are amply sufficient, and the operator is enabled to effect the drawing off while seated. Finally, the cocks, which are very simple and strong and easily operated, are completed by an apparatus for automatically drawing off the froth. The nozzles of the cocks are provided with an inverted-cone trunk made of flexible india-rubber, which effects a junction with all the bottle-necks even when the latter are indented.

In order that the object of the invention may be understood, it is illustrated in the accompanying drawings, in which—

Figures 1 and 2 are respectively a front and a side view of the machine. Fig. 3 is a longitudinal section, on a larger scale, of one of the distributing-cocks; Fig. 4, a transverse section of the same; Fig. 5, a view of the same from below; Fig. 6, an end view of the same on the side where the machine is worked; Fig. 7, a view in detail of the means of working the screens; Fig. 8, a detail view of the means of working the distributing-cocks combined with that of the screens.

The machine thus illustrated is composed of a cast-iron table *a* and two frames *b*. Through this table run the rods *c* of two platforms *d*, movable in guides. Each platform is raised by a counterweighted lever *e*, the end of which enters a slot in the guide. These platforms, the rods of which are longer or shorter, according to the dimensions of the bottles, press the bottles against the india-rubber packings *f* of the cocks *g*. In order to release the bot-

titles, the levers *e* are lowered by pedals *h*, the fulcrums of which are jointed to a compressed-gas reservoir *i*. This reservoir *i*, which connects the two frames *b*, is filled two-thirds full with glycerinated water, (compensating liquid.)

k is a junction intended for the india-rubber tube which conveys the compressed air or carbonic acid from the generating-receptacle to the reservoir *i*.
60

l is a discharge-cock for conveying the compressed gas out of *i* as required and causing the compensating liquid which has risen in the cylinder *m* to descend.

A pipe *n* starts from the bottom of *i* and runs through the column *o* to the glass cylinder *m*. The float *p* is arranged to close the opening *q* running to the outside of the cylinder. The pipes *r* connect the upper part of the cylinder with the air-passages *s*, cut through the cocks *g*, Figs. 3 and 4. These cocks, which have conical plugs and are screwed up more or less tightly by a nut *t* and a washer *u*, Fig. 5, have two passages of unequal diameter running through them. The one *r*, of six to seven millimeters in diameter, conveys the beer through the junction situated behind the column and through the interior of the arms which support the cocks. The compressed-air tubes *r* are extended, as mentioned above, by the passages *s*, which are divided in the plug of the cock into two oblique passages connected by another passage *w*, and thus forming a triangle. The base *w* of this triangle is in constant communication with the pipes, while the apex of the triangle is alternately in communication with an apparatus for drawing off foam and with the bottle to be filled. Under this arrangement the compressed air enters the empty bottles well 85 in advance of the beer, and as soon as the air and the beer meet in the bottles the passages in the plug of the cock communicate with pipes *x*, which lead to a three-way cock *x'*, and the outlet-opening of which is also furnished with an india-rubber cone, against which the neck of a bottle *y* fits and into which the froth is discharged. This bottle is supported and held under the cock *x'* by a balance-lever *y'*.
90

100

The opening and closing of the distributing-cocks g , Figs. 2 and 8, are effected by levers z , pivotally connected with connecting-rods a' , which actuate the keys b' , solidly connected 5 with the cocks g .

Screens c' are arranged vertically between the platforms d and the distributing-cocks, their opening and closing being effected simultaneously, but inversely with the opening 10 and closing of the cocks g and by the simple operation of the levers z described. For this purpose the bottom of each of the connecting-rods forms a projection a^2 , on which a lever z' rests, the end of which opposite to the pivot 15 is raised by a belt d' , which passes over a pulley d' and thence around a pulley e' , the axis f' of which is the pivot of the corresponding screen. From this pulley the belt passes over a second vertical pulley g' and 20 supports a counterweight h' , Fig. 7.

The bottom of the connecting-rod a' , already described, may assume the positions a^3 , a^4 , and a^5 . In Fig. 7 the bottom a^5 has returned to a^4 and nearly closed the cock g . In raising 25 the rod from a^4 to a^3 the lever effects the closing of this cock. In Fig. 7 the cock g is closed and the lever z' is about to lower the rod from a^3 to a^4 , which effects the closing of c' . Then when the lowering is continued 30 from a^4 to a^5 the key b' will fall to b^2 , Fig. 8, the opening point of the cock which corresponds to a^5 .

When the cylinder m is arranged a little above the cocks g and these cocks being at a 35 suitable height to permit the workman to work while sitting down, the compensating liquid must necessarily be about the same density as the beer. The density might be less if the cylinder were higher, and, on the contrary, this 40 density might be greater than that of the beer if the cylinder were lower, (which would interfere with the manipulation of the bottles.) Thus the density of the compensating liquid need be about the same density as that of the 45 beer only in case of the practical arrangement of the parts as seen in the drawings.

Action: From the foregoing it will be seen that the compressed gas must first be conveyed from the generating-receptacle, which 50 is independent of the machine, into the reservoir i . Under its action the compensating liquid rises in the cylinder m , raises the float, and forms in the upper part of the cylinder a second air-chamber, the pressure of this air 55 being lower than that of the generating vessel by the whole weight of the column of liquid between i and m . The compressed air in the cylinder creates the counter-pressure in the empty bottles through the pipes r and the 60 passages w in the cocks. The beer in turn reaches the bottles, and as it is forced by the same compressed-gas receptacle as the compensating liquid and has less distance to ascend than the latter it drives the air contained 65 in the bottles before it, fills the bottles, and

if the closing of the cocks be not effected rises again in the pipes r only up to the level of the float p . When the quantity of air forced out of the bottles into the cylinder becomes too large, the compensating liquid sinks with 70 the float p , which then allows the excess of air to escape through the orifice q . The beer which has been able to ascend again in the air-pipes r runs off during the closing of the cocks into the froth-receptacle y through the 75 pipes x . This beer cannot thus be discharged in a foaming condition into the fresh bottles to be filled and is recovered in y .

What I claim is—

1. In an apparatus of the character described, the combination of a supporting-frame, a lower receptacle containing a liquid as described, an upper cylinder with which the lower receptacle is in communication, an outlet in the upper cylinder, a float adapted 80 to close the said outlet, pipes r leading from the upper cylinder, a distributing-cock having passages with which the pipes r communicate, the said passages having the triangular arrangement described, said cock also having 85 the passage v , a pipe communicating with the passages having the triangular arrangement, and means for operating the distributing-cock.

2. In an apparatus of the character described, the combination of a supporting-frame, a lower receptacle containing a liquid as described, an upper cylinder with which the lower receptacle is in communication, an outlet in the upper cylinder, a float adapted to 90 close said outlet, pipes r leading from the upper cylinder, distributing-cocks having passages with which the pipes r communicate and having the triangular arrangement described, said cocks also having each a passage v , pipes x 95 communicating with the passages having the triangular arrangement, and a cock x' with which pipes x communicate.

3. In an apparatus of the character described, the combination of a supporting-frame, a lower receptacle containing a liquid as described, an upper cylinder with which the lower receptacle is in communication, an outlet in the upper cylinder, a float adapted to 100 close said outlet, pipes r leading from the upper cylinder, distributing-cocks having passages with which the pipes r communicate and having the triangular arrangement described, said cocks also having each a passage v , pipes 105 communicating with the passages having the triangular arrangement, and a cock x' with which pipes x communicate, the vertically-movable platforms d and counterweighted levers carrying the platforms.

4. In an apparatus of the character described, the combination of a supporting-frame, a lower receptacle containing a liquid as described, an upper cylinder with which the lower receptacle is in communication, an outlet in the upper cylinder, a float adapted to 115

close said outlet, pipes *r* leading from the upper cylinder, distributing-cocks having passages with which the pipes *r* communicate and having the triangular arrangement described, 5 said cocks also having each a passage *r*, pipes communicating with the passages having the triangular arrangement, and a cock *w* with which pipes *w* communicate, and a pivoted lever carrying a counterbalance *y*.

10 5. In an apparatus of the character described, the combination of a supporting-frame, a lower receptacle containing a liquid as described, an upper cylinder with which the lower receptacle is in communication, an outlet in the upper cylinder, a float adapted to close said outlet, pipes *r* leading from the upper cylinder, distributing-cocks having passages with which the pipes *r* communicate and

having the triangular arrangement described, said cocks also having each a passage *r*, pipes 20 communicating with the passages having the triangular arrangement, and a cock *w* with which pipes *w* communicate, levers *z*, rods connecting said levers with the distributing-cocks, the movable platforms *d*, screens arranged between the platforms and the distributing-cocks and means intermediate the connecting-rods and the screens for operating the latter.

In testimony that I claim the foregoing I 30 have hereunto set my hand this 12th day of August, 1902.

JOSEPH DELAITTRE.
